His Attorney.

UNITED STATES PATENT OFFICE

CHARLES F. SCHWENNKE, OF SCHENECTADY, NEW YORK, ASSIGNOR TO GENERAL ELECTRIC COMPANY, A CORPORATION OF NEW YORK

ELECTRIC SWITCH

Application filed September 29, 1927. Serial No. 222,891.

My invention relates to electric switches and particularly to switches having high current-carrying capacity. An object of my invention is the provision of an improved switch in which the cooperating contacts have a rolling contact with each other and in which a minimum length of relative movement thereof is required from the point of initial contact to the point of complete contact. Another object of my invention is the provision of a switch comprising a fixed contact having a plurality of contact rollers and having a minimum length in the direction of movement of the rollers. Other objects of my invention will appear as the detailed description progresses.

My invention will be better understood from the following description taken in connection with the accompanying drawing, and its scope will be pointed out in the appended claims.

Referring to the drawing, Fig. 1 is a fragmentary view of an oil switch embodying my invention; Figs. 2 and 3 are details of the switch contacts respectively in closed and open circuit positions; and Fig. 4 is an exploded view of the parts of the fixed contact.

While my invention is adapted for use in either an air break switch or a fluid break switch, I have chosen to illustrate it as forming a part of an oil switch.

In Fig. 1 I have shown the tank 1 of the oil switch containing insulating oil 2 into which projects the insulator bushing 3. Attached to the bushing is the adapter 4 supporting the fixed contact 5 and the explosion chamber 6. The complete switch includes another similar construction, the two being connected when the switch is closed by the yoke 7 carrying at each end the movable contact rod 8 which has a slightly tapered end and in the present case is square in cross section.

The fixed contact 5 comprises the casing 9 which is shown screw-threaded into the bottom of the adapter and by which the contact members are supported. Within the casing are four contact plates 10 arranged in a square, each plate in the present example comprising three similar sections 12, the ends

of the plates being beveled as at 13 to form miter joints. Between each section 12 and the adjacent portion of the casing are resilient means pressing them toward the center of the casing. I have shown this means as a number of arcuate springs 15 having somewhat greater curvature than the inner surface of the casing. These springs are arranged in groups and between groups are the curved spacers 16 whose curvature is substantially the same as that of the casing but which are somewhat shorter than the springs so as not to interfere with the outward yielding movement of the plate sections. Two widths of spacers are shown, those of the wider width being used opposite the joints between plate sections. The four assemblies of springs and spacers are retained in place in the casing by the arcing bell 18 which is secured to the casing by the bolts 19 passing through its flanged edge. For providing good electrical connection between the casing and the several plate sections without interfering with their free relative movement, I connect the sections together with flexible copper straps 20. The straps are shown secured to the sections by the plates 21 and screws 22 and the upper ends of the straps are firmly secured to the upper portion of the casing by the bolts 23, the straps passing through suitable openings in the casing. The straps not only provide the electrical connection to the sections but maintain them in proper relative position with just enough clearance between them to insure the desired freedom of movement thereof.

Within the four contact plates 10 are four sets of rollers, each set shown as comprising three rollers 25 which make rolling engagement with the corresponding plates 10 and the contact rod 8 when the rod is moved to closed circuit position. The upper and intermediate rollers of the four sets are held together to form a hollow square by a harness or cage comprising the four angle plates 27 and the bearing pins 28 fixed thereto upon which pins the rollers are loosely journalled. The lower roller of each set is suspended from the pin of the intermediate roller by the links 29 and pin 30 fixed thereto, the lower roller being 100

loosely journalled on the pin 30 as are the other rollers. While it is desirable to have the lower rollers free to swing outwardly in order to assume the position shown in Fig. 3, it is undesirable to have them swing inwardly as such might interfere with the entering of contact rod 8. I have accordingly provided a hump 32 on each link 29, one end of which will engage as a stop, an extension 33 on the angle plate 27. The roller assembly is free to move a limited distance vertically in the casing whilst the separate rollers engage on opposite sides the contact rod and the contact plate sections, the springs behind the plates being constructed to produce the required contact pressure against the rollers to make good electrical contact. The arcing bell as shown particularly in Fig. 4 is provided with four pockets 35 and with a central upwardly extending flange 36. The pockets are shaped to receive the lowermost roller of each set and are positioned back from the central opening for the contact rod, the flange 36 functioning to withdraw the lower roller from the rod as the same is withdrawn. In the open circuit position of the rollers the lower rollers, as shown in Fig. 3, rest in the pockets in positions opposite the ends of the contact plates and out of contact therewith.

As the contact rod 8 moves upward in its circuit closing movement, it first engages and begins to roll on the intermediate roller whence the entire roller assembly begins movement upward. As this movement continues the rod subsequently engages the upper roller and the lower roller is drawn upward and inward to a position between the rod and the contact face of the lower section 12 of the contact plate. In the final closed circuit position of the rod each of the twelve rollers is in firm contact with the rod and with a corresponding number of contact plate sections, the contact pressure against each roller being governed by the tension of the springs behind each plate section. An important advantage of this construction is that it requires less travel of the contact rod to effect full contact with all of the rollers. This will be the more apparent when it is considered that the axis of a roller moves only one half the distance of the member rolling thereon and that were all the three rollers engaged at all times by the rod and a contact plate the rod would have to be moved a minimum distance of at least that equal to twice the distance between the axes of the upper and the lower rollers. By causing the lower roller to swing into position in response to upward movement of the other rollers, it is necessary to move the rod only one half as far or a minimum distance equal to that between the axes of the upper and lower rollers. Practically the rod will be moved somewhat further than the theoretical minimum distance, the upper end of the rod in

the closed circuit position of the switch preferably extending a little beyond the upper roller as shown, for example, in Fig. 2. As the rod is withdrawn the reverse operation of the rollers takes place, the lower roller after passing the lower plate section being deflected outwardly by the flange 36 into the pocket 35. The final break in the circuit occurs between the rod and the intermediate roller which roller takes any burning that may occur; an arc if formed, however, is transferred to the arcing bell 18. Not only is a shorter stroke of the rod required between its initial and final contact positions but a correspondingly shorter entire fixed contact is required. Should the intermediate rollers of the roller assembly for any reason fail to begin to roll on the rod when first engaged thereby, but be pushed bodily upward by the end of the rod, the subsequent clamping action of the lower roller between the rod and the contact plate would immediately arrest such movement and cause the rod to begin to roll on the rollers.

What I claim as new and desire to secure by Letters Patent of the United States, is—

1. An electric switch having relatively movable contacts, one of said contacts comprising a plurality of rollers for engaging the other contact, and means responsive to movement of one of said rollers for causing another of said rollers to move into and out of engagement with said other contact.

2. An electric switch having relatively movable contacts, one of said contacts comprising a plurality of connected rollers, one of said rollers being withdrawn from the path of movement of said other contact when the switch is in open circuit position and means responsive to the circuit closing movement of said contacts for causing said one roller to move toward and engage said other contact.

3. An electric switch having cooperating rod and roller contact members, said roller contact member comprising a contact plate and a plurality of connected rollers arranged to engage the plate and the rod when the switch is closed and means for withdrawing one of said rollers from said rod when the switch is being opened.

4. An electric switch comprising a contact rod, a cooperating roller contact member comprising a contact plate, a roller for engaging the rod and contact plate, a second roller connected with the first roller and arranged to be moved thereby from a position out of engagement with the plate and the rod to a position in engagement with the same.

5. An electric switch having a movable contact rod, and a fixed contact comprising a contact plate, a pair of rollers engaging the plate, and arranged to be engaged by said rod, and a third roller connected to one

of said other rollers and arranged to be moved thereby from a position displaced from said plate to a position between the plate and the contact rod.

5 6. An electric switch having a movable contact rod and a fixed contact comprising a contact plate, a plurality of rollers arranged to have rolling contact with the face of the plate and to be successively engaged by the contact rod, one of said rollers being displaced from the face of the plate when the rod is in open circuit position and means responsive to movement of another of said rollers for drawing said one roller from its 10 displaced position to a position between the plate and the rod.

15 7. An electric switch having a movable contact rod and fixed contact comprising a contact plate, a plurality of rollers arranged 20 to make rolling contacts with the rod and the plate and means for withdrawing one of said rollers out of the path of the rod when the rod is being moved to open circuit position.

25 8. An electric switch having a movable contact rod and a fixed contact comprising a contact plate, a plurality of rollers arranged to make rolling contact with the plate and the rod and a member having a 30 pocket arranged to receive one of said rollers and hold the same out of the path of the rod when the same is withdrawn from the fixed contact.

35 9. An electric switch having a fixed contact comprising a casing, a contact plate therein having a plurality of sections, resilient means between each section and the casing, flexible conductors connecting together said sections, and a plurality of 40 rollers adapted to engage on opposite sides the respective sections and a cooperating movable contact rod.

45 10. An electric switch having a fixed contact comprising a casing, a plurality of contact plates therein each having a plurality of sections, resilient means between each section and the casing, flexible conductors connecting together and to the casing, a plurality of sets of rollers adapted to engage 50 the respective sections and to engage opposite sides of a cooperating movable contact rod and a roller retaining member arranged in the open circuit position of the rod to retain one roller of each set in a position 55 laterally displaced from the plates and the rod.

In witness whereof, I have hereto placed my hand this 28th day of September, 1927.

CHARLES F. SCHWENNKER.
